DESIGN FOR A RUG.

Design No. 16,094, dated May 19, 1885.

UNITED STATES PATENT OFFICE.

RICHARD PAUL HEMMING, OF PHILADELPHIA, PENNSYLVANIA, ASSIGNOR
TO GEORGE W. ENNIS & CO., OF SAME PLACE.

DESIGN FOR A RUG.

SPECIFICATION forming part of Design No. 16,094, dated May 19, 1885.

Application filed April 16, 1885. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in a triple-panel center. The middle panel is ornamented by branches, leaves, flowers, and a cross-border at each end, dividing the center from the end panels. The end panels are

ornamented by figures known as the "India" style of ornamentation. The panels are surrounded by a triple border. The middle border represents groups of foliated ornamentation. The inner and outer borders represent ornamental moldings—the whole as shown in the photographic print accompanying this specification.

What I claim as my invention is—

The design for a rug, as shown and described.

R. PAUL HEMMING.
